UNITED STATES PATENT OFFICE

158,095

VAPORIZER COVER OR SIMILAR ARTICLE

Max Katzman, Brooklyn, N. Y.

Application October 28, 1948, Serial No. 149,349

Term of patent 14 years

(Cl. D83—1)

To all whom it may concern:

Be it known that I, Max Katzman, a citizen of the United States, residing in Brooklyn, county of Kings, and State of New York, have invented a new, original, and ornamental Design for a Vaporizer Cover or Similar Article, of which the following is a specification, reference being had to the accompanying drawings, forming a part thereof, in which

Fig. 1 is a top plan view of a vaporizer cover or similar article showing my new design;

Fig. 2 is a view in side elevation of the vaporizer cover or similar article;

Fig. 3 is a bottom plan view of the vaporizer cover or similar article;

Fig. 4 is a view in rear elevation of the vaporizer cover or similar article; and

Fig. 5 is a view in front elevation of the vaporizer cover or similar article.

I claim:

The ornamental design for a vaporizer cover or similar article, as shown.

MAX KATZMAN.
